PUSH-BAR BRACKET OR SIMILAR ARTICLE

Norman Cutler, 400 Salisbury Road, Wyncote, Pa.

Filed Nov. 8, 1962, Ser. No. 72,426

Term of patent 14 years

(Cl. D10—8)

FIG. 1 is a perspective view of a push-bar bracket or similar article embodying my new design. The sides not shown are mirror images of the respective sides shown.

FIG. 2 is a perspective view of a modification of the push-bar bracket or similar article shown in FIG. 1. The sides not shown are mirror images of the respective sides shown.

I claim:

The ornamental design for a push-bar bracket or similar article, as shown and described.
